DESIGN FOR A PENHOLDER

Boris Blecher, Philadelphia, Pa.

Application November 1, 1946, Serial No. 134,446

Term of patent 14 years

(Cl. D74—1)

To all whom it may concern:

Be it known that I, Boris Blecher, a citizen of the United States and a resident of Philadelphia, county of Philadelphia, State of Pennsylvania, have invented a new, original, and ornamental Design for a Pen Holder, of which the following is a specification, reference being had to the accompanying drawings, forming a part thereof, wherein:

Figure 1 is a perspective view of a pen holder, showing the essential features of my new design in full lines, the pen receptacle element shown in broken lines in Figure 1 being omitted from the other figures for convenience of illustration;

I claim:

The ornamental design for a pen holder, as shown and described.

BORIS BLECHER.
